UNITED STATES PATENT OFFICE.

GEORGE B. SMITH, OF INDIANOLA, NEBRASKA.

CORD-ADJUSTER.

No. 833,009.

Specification of Letters Patent.

Patented Oct. 9, 1906.

Application filed April 28, 1906. Serial No. 314,180.

To all whom it may concern:

Be it known that I, GEORGE B. SMITH, a citizen of the United States, residing at Indianola, in the county of Redwillow and State of Nebraska, have invented new and useful Improvements in Cord-Adjusters, of which the following is a specification.

This invention is a cord-adjuster, and more particularly a device of this kind for the suspension-cord or circuit-wires of an incandescent lamp.

The object of the invention is to provide a simple and efficient device whereby the lamp can be readily raised or lowered to different heights.

A further object is to provide an adjuster which can be attached without removing the lamp or other fixtures and which will securely grip the cord and hold the lamp at the desired elevation.

In the accompanying drawings, Figure 1 is a side elevation of the invention. Fig. 2 is a top plan view.

Referring specifically to the drawings, the adjuster is made of a single piece of spring-wire which is looped, as at 5, to form a handle. The free ends 6 and 7 of the wire are then brought together and extended in opposite directions, being fastened together by a sleeve 8, passing around the same. At opposite ends of the loop the wire is extended laterally and bent to form clasps 9 and 10, respectively. The clasps are formed by bending the wire forwardly from the loop for a short distance, as at 11. A return-bend 12 is then made and the wire is extended rearwardly toward the loop substantially parallel to the part 11. A bend 14 is then made across the part 11, and the wire is again bent forwardly, as at 15, along said part, its ex-

tremity being bent slightly sidewise, as at 16, to facilitate the entrance of the cord between the parts 11 and 15, which form the jaws of the clasp. The adjuster is made of spring-wire, by reason of which the cord will be securely held between the jaws of the clasp.

In use the lower clasp is first applied to the cord, and it is then elevated to the desired height. After this the top clasp is applied, the slack cord being extended through the loop 5, as shown in Fig. 1. The lamp can be readily lowered by pulling it down, as the grip of the clasps is only sufficient to sustain the weight of the lamp.

An adjuster constructed as herein described can be cheaply produced, and it effectively serves the purpose for which it is intended. A further advantage is that it can be applied or removed without disturbing the lamp or other fixtures.

I claim—

1. A cord-adjuster comprising a single piece of wire which is looped to form a handle, the free ends of the wire being extended laterally from opposite ends of the loops, and bent to form resilient clasps.

2. A cord-adjuster comprising a single piece of wire which is looped to form a handle, the free ends of the wire being extended laterally from opposite ends of the loops, and having rearward and forward bends to form resilient clasps.

In testimony whereof I have signed my name to this specification in the presence of two subscribing witnesses.

GEORGE B. SMITH.
